UNITED STATES PATENT OFFICE.

THOMAS M. FREEBLE, OF ROCHESTER, PENNSYLVANIA, ASSIGNOR OF ONE-HALF TO
RAYMOND M. KAUFMANN, OF PITTSBURGH, PENNSYLVANIA.

MANUAL ACTUATOR FOR RAILWAY-SIGNALS.

1,155,477.

Specification of Letters Patent.

Patented Oct. 5, 1915.

Application filed October 8, 1912. Serial No. 724,595.

To all whom it may concern:

Be it known that I, THOMAS M. FREEBLE, a resident of Rochester, in the county of Beaver and State of Pennsylvania, have invented a new and useful Improvement in Manual Actuators for Railway-Signals, of which the following is a full, clear, and exact description, reference being had to the accompanying drawings, forming part of 10 this specification, in which—

Figure 1 is a plan view illustrating one form of my invention. Fig. 2 is a transverse section of the same. Figs. 3, 4 and 5 are views similar to Fig. 2, but showing 15 other forms of the invention. Fig. 6 is a detail sectional view of one form of indicator which may be employed. Fig. 7 is a view similar to Fig. 2, but showing another modification; and Fig. 8 is a diagram showing 20 the use of my invention.

My invention has relation to manual actuators for railway track signals. It frequently happens that a track obstruction will occur in a block section of a railway 25 signaling system, which is of such a nature that it will not set the signal or signals guarding the entrance to that block at danger. For instance, there may be some projection overhanging the track; there may 30 be a landslide covering one of the rails; or various other conditions may occur which will not effect a short circuiting of the signal operating relay for the block section in which the obstruction occurs.

35 My invention provides means of simple character which, in such cases, can be readily applied to the track rails to throw the proper signals to danger positions at any point in the block, and without the necessity for sending a signal man or other person back along the track to flag an approaching train.

To this end my invention consists of a manual device which, in its preferred form, 45 can be readily carried either in the pocket or in some convenient place where it can be quickly reached and which can be readily applied to the track rails to short circuit them and set the proper signal or signals 50 at danger position.

The simplest, although not the preferred, form of my invention is illustrated in Fig. 7. In this figure the device is shown as consisting of a bar 2 of conducting material 55 adapted to be engaged with the heads of the

track rails 3 and to be secured thereto by the set screws 4. These screws form a means of closely binding the hooked end portions of the bar in a good electrical contact with the heads of the rails, so that as soon as 60 properly applied thereto it will at once effect a short circuit.

In Figs. 1 and 2, I have shown another form of my invention comprising two hooked contact members 5 adapted for application to the heads of the rails and secured thereto by set screws 6. These two members are connected by a flexible conducting tape 7, which is preferably provided with a winding case 8, mounted on one of 70 the members 5. This member 5 is also preferably provided with an indicator 9, which will indicate the fact that a short circuit has been obtained. This indicator may be of 75 any suitable or well known character. One form of such indicator is shown in Fig. 6. It consists of low resistance field magnets 10, between the poles of which is mounted a rotary indicator armature having metallic 80 portions 11 and nonmetallic portions 12. This indicator armature is so balanced that it will normally stand in the position shown in Fig. 6 with its nonconducting portions opposite the poles of the magnets. When, however, the magnets are energized, the 85 armature will be rotated to a position in which its magnetic portions are in the axial line of the field magnets. This brings a suitable indicator 13 thereon, underneath a sight opening 14 in the inclosed casing 15. This indicator is shown as connected in 90 series between the bridging portion of the device and one of the set screws 6. Thus, in Fig. 2, one connection of the indicator is 95 with one set screw 6 and its other connection is to the tape 7, the tape case being insulated at 8^a from the contact member 5.

Fig. 3 shows another form of my invention in which the bridge portion of the device is composed of a plurality of telescoping sections 16 which can be readily closed upon each other to form a compact device.

Fig. 4 shows another form which is adapted to be held in electrical contact with the heads of the rails by means of the eccentric clamps 17. The connecting portion 18 of the device is shown as having an insulated joint at 18^a.

Fig. 5 shows still another form in which the connecting portion of the device is 110

formed by a plurality of folding jointed sections 19, which are capable of being folded in the manner of the sections of an ordinary pocket rule.

5 My invention is also susceptible of various other modifications.

It will be readily seen that if the device is applied across the rails, as shown in Fig. 8, at any point in a block section between 10 the source of current supply 20 for that section and the signal operating relay 21, the latter will be immediately short circuited and set the signal 22 at danger.

The device can be quickly applied to the 15 rails and forms a quick and sure method of preventing the approach of a train into an obstructed block.

I claim:

1. A manual actuator for track signals, 20 comprising a conductor adapted to bridge two opposite track rails and having contact members at its ends for engagement with the rails, one of said members having a low resistance current indicator; substantially 25 as described.

2. A manual actuator for track signals, comprising a conductor adapted to bridge two opposite track rails and having contact members at its ends for engagement with the rails, one of said members having a low 30 resistance current indicator, said indicator being in series with the bridging conductor; substantially as described.

3. A manual actuator for track signals comprising a conductor adapted to bridge 35 two opposite track rails and having contact members at its ends for engagement with said rails, the two contact members having insulation between them, and a current indicator mounted on one of the contact members and connected in series between the two contact members; substantially as described.

In testimony whereof, I have hereunto set my hand.

THOMAS M. FREEBLE.
